US00D632292S

(12) **United States Design Patent**
Yang et al.

(10) **Patent No.:** US D632,292 S
(45) **Date of Patent:** ** Feb. 8, 2011

(54) **CARD READER**

(75) Inventors: **Tianzhu Yang**, Shenzhen (CN);
Zhixiong Li, Shenzhen (CN)

(73) Assignee: **Shenzhen Netcom Electronics Co., Ltd.**, Shenzhen (CN)

(**) Term: **14 Years**

(21) Appl. No.: **29/346,111**

(22) Filed: **Oct. 27, 2009**

(51) LOC (9) Cl. **14-02**

(52) U.S. Cl. **D14/385**

(58) **Field of Classification Search** D14/383-389,
D14/356-358, 361, 363, 432-438; 235/441,
235/451, 492, 380, 439, 375; 361/679.31,
361/600, 679.01, 679.02
